UNITED STATES PATENT OFFICE.

ALLISON W. LAWSON, OF MIDWAY, ALABAMA.

RINGING BURGLAR-ALARM.

SPECIFICATION forming part of Letters Patent No. 277,296, dated May 8, 1883.

Application filed February 16, 1883. (No model.)

To all whom it may concern:

Be it known that I, ALLISON W. LAWSON, of Midway, in the county of Bullock and State of Alabama, have invented certain new and useful Improvements in Door-Alarms; and I do hereby declare that the following is a full, clear, and exact description of the invention, which will enable others skilled in the art to which it appertains to make and use the same, reference being had to the accompanying drawings, which form a part of this specification, and in which—

Figure 1 is a perspective view of a part of a door and door-frame provided with my improved alarm, with part of its inclosing-casing broken away; and Fig. 2 is a front view of the alarm.

Similar letters of reference indicate corresponding parts in both the figures.

20 My invention has relation to that class of door-alarms adapted to be fastened to the frame of a door and to be operated by a projection upon the edge of the door, which, when the door is opened or closed, will strike a projection upon a bell-hammer, sounding a bell; and it consists in the detailed construction and combination of parts of the same, as hereinafter more fully described and claimed.

In the accompanying drawings, the letter A indicates the casing or frame, in which the bell B and its operating-spring C are fastened, the back piece, D, of the casing having both ends E projecting, for the purpose of fastening it to the door-frame above the door. The bell B is fastened to the front piece, F, of the casing upon a lug or bolt, G, while the spring C, upon the outer end of which is a hammer, H, is fastened in one end of the casing. This spring is fastened in the side of a recess, I, in one of the end pieces, J, of the frame, its inner bent end, K, being inserted into the side of the recess, whereupon it passes down the side of

the recess, and is clamped to the side of the recess by means of staples L. The spring is thereupon coiled, forming a spiral, M, and carried out to one side, forming a downward-projecting bail, N, and curved upward and downward at its outer end, so as to project inside the bell, the hammer H being in close proximity to the lower portion of the rim. A roller, O, pivoted in a bracket, P, upon the upper edge of the door, engages bail N when the door is opened or closed, pushing it and the spring upward, causing the hammer to strike the bell as the spring rebounds.

It will thus be seen that the door cannot be opened or closed without giving alarm, and that by the simplicity of construction of the spring the alarm does not easily get out of order.

By making slight changes in the arrangement of the roller and spring the alarm may be applied at any place or object—such as shutters, drawers, trunks, &c.—without changing the spirit of my invention.

Having thus described my invention, I claim and desire to secure by Letters Patent of the United States—

In a door-alarm, the combination of spring C, fastened in a recess, I, in the end piece of the inclosing-casing A by its bent end K and staples L, said spring being bent to form the spiral M and bail N, and having hammer H, with the bell B, fastened to the front piece of the frame A, and roller O, pivoted in bracket P upon the upper edge of the door, as and for the purpose shown and set forth.

In testimony that I claim the foregoing as my own I have hereunto affixed my signature in presence of two witnesses.

ALLISON W. LAWSON.
